UNITED STATES PATENT OFFICE.

GEORGE W. BARRICKLOW, OF AKRON, OHIO.

DESIGN FOR A VEHICLE SIGNAL-LAMP CASING.

Application filed May 28, 1924. Serial No. 9,728. Term of patent 14 years.

To all whom it may concern:

Be it known that I, GEORGE W. BARRICKLOW, a citizen of the United States, residing at Akron, in the county of Summit and State of Ohio, have invented a new, original, and ornamental Design for Vehicle Signal-Lamp Casing, of which the following is a specification, reference being had to the accompanying drawing, in which the figure is a perspective view of a vehicle signal-lamp casing and embodying my design.

I claim:

The ornamental design for a vehicle signal lamp casing, as shown.

In testimony whereof I have hereunto set my hand.

GEORGE W. BARRICKLOW.
